G. A. SMITH.

REINFORCING DEVICE FOR CONCRETE STRUCTURES,
APPLICATION FILED SEPT. 20, 1919.

1,331,288.

Patented Feb. 17, 1920.

UNITED STATES PATENT OFFICE.

GEORGE ALBERT SMITH, OF TORONTO, ONTARIO, CANADA.

REINFORCING DEVICE FOR CONCRETE STRUCTURES.

1,331,288.

Specification of Letters Patent.

Patented Feb. 17, 1920.

Application filed September 20, 1919. Serial No. 325,219.

To all whom it may concern:

Be it known that I, GEORGE ALBERT SMITH, a British subject, and resident of the city of Toronto, in the county of York and Province of Ontario, Dominion of Canada, have invented certain new and useful Improvements in Reinforcing Devices for Concrete Structures; and I hereby declare the following to be a full, clear, and exact 10 description of the same.

My invention relates to concrete structures, such as walls, building blocks, and the like, reinforced by rods, bars, or other elements of a like nature, embedded in the 15 concrete mixture, and the object of my invention is to so devise these elements that any number of them may be set in the mold or form prior to the concrete mixture being placed therein and maintained in their set 20 position within the mold or form by the pressure they exert against its sides.

In carrying out the invention the reinforcing elements are set end to end and a spring is interposed between their adjacent 25 ends to press them asunder, and cause their outer ends to impinge on and exert such pressure against the sides of the mold or form as to maintain the elements in their set position before and while the concrete 30 is being placed in the mold or form, as hereinafter set forth and particularly pointed out in the claims.

In the drawings:

Figure 1, is a sectional elevational view 35 showing the erection of a concrete wall,

Fig. 2, is a sectional elevational view of a reinforcing element composed of a pair of bars or rods set end to end, a spring interposed between their adjacent ends, and a 40 casing for the spring,

Fig. 3, is a detail view of the inner end of one of the bars or rods, shown in Fig. 2, and

Fig. 4, is a similar view to Fig. 3 of the 45 outer end.

Like characters of reference refer to like parts throughout the specification and drawings.

In the erection of concrete walls, a form 50 or mold comprising two vertical sides a, a' , is employed, and the reinforcing elements a'' for the concrete mixture are set transversely of the form or mold to impinge against the sides a, a' .

55 In Fig. 1, I have shown three of these

reinforcing elements within the mold or form placed one vertically above the other in perpendicular alinement, but they may be set in any other relation.

In order to maintain the reinforcing elements in their set position in the form or mold, I make each of them in two parts b, b' , set end to end with an intervening interval c between their adjacent or inner ends, in each of which is formed a recess d, d' , to receive the extremities of a helical spring e . This spring is slightly greater 60 in length than that of the interval c , and is preferably inclosed by a casing or sleeve f , which overlaps the inner ends of the parts b, b' , to prevent the concrete entering 65 between its convolutions.

The outer ends h of the parts b, b' , are tapered as shown in Figs. 1 and 2, to reduce 70 their contact surface with the sides a, a' , and to provide for the outer ends of the reinforcing elements being incased or covered substantially for their whole cross-sectional area with the concrete mixture along the 75 surfaces of the wall.

For a wall twelve inches in width, I employ a reinforcing element constructed as above, in which the parts b, b' , are each 80 about five inches in length and about one inch square in cross section, with the outer 85 ends tapered to about one-eighth of an inch square. In the inner ends of the parts b, b' , I form the recesses d, d' , each approximately one-half to five-eighths of an inch in diameter and about one-quarter of an inch in 90 depth, to receive the spring e , which is of corresponding diameter, and about three inches in length. This necessitates the spring being contracted to about two and one-half inches in length when placing the 95 parts of the reinforcing element in position and enables the spring to exert a corresponding pressure on the parts b, b' , and force their outer ends into engagement with the sides a, a' , of the form or mold and thus 100 hold the reinforcing element in its set position before and while the concrete is being placed therein.

When reinforcing elements g, g' , are employed they are arranged transversely of the 105 parts b, b' , in which are formed apertures or slots b^3, b^4 , for these transverse reinforcing elements to pass through.

In the case, however, of concrete building blocks it may or may not be necessary to use 110

the reinforcing elements g , g' , and in the latter case they, and the apertures or slots b^3 , b^4 , may be omitted.

Having thus fully described my invention, 5 what I claim as new and desire to secure by Letters Patent is:

1. A reinforcing device for concrete structures comprising a reinforcing element, consisting of two parts set end to end, and a 10 spring inserted between the adjacent ends of said parts to spread them asunder.

2. A reinforcing device for concrete structures comprising a reinforcing element, consisting of two parts set end to end, a spring 15 inserted between the adjacent ends of said parts to spread them asunder, and a casing for the spring overlapping the adjacent ends of said parts.

3. A reinforcing device for concrete structures comprising a reinforcing element, con- 20

sisting of two parts set end to end, a spring inserted between the adjacent ends of said parts to spread them asunder, and reinforcing elements inserted transversely through the first mentioned reinforcing element.

25

4. A reinforcing device for concrete structures comprising a reinforcing element, consisting of two parts set end to end, a spring inserted between the adjacent ends of said parts to spread them asunder, a casing for 30 the spring overlapping the adjacent ends of said parts, and reinforcing elements inserted transversely through the first mentioned reinforcing element.

Toronto, September 3rd, 1919.

GEORGE ALBERT SMITH.
